UNITED STATES PATENT OFFICE.

JAMES A. CAMERON, OF BROOKLYN, NEW YORK, ASSIGNOR TO CAMERON MACHINE COMPANY, OF BROOKLYN, NEW YORK, A CORPORATION OF NEW YORK.

WINDING MEANS.

Application filed August 13, 1925, Serial No. 49,949. Renewed June 4, 1926.

This invention relates generally to winding machines; and has more particularly reference to a reeling means associated with a paper-making or other machine from which a web of flexible material flows uninterruptedly.

In an application filed July 6, 1925, Ser. No. 41,495, there is disclosed winding mechanism in which the winding shaft is initially 10 out of engagement with the surface winding drum, there being a driving mechanism for initially rotating the winding shaft before it engages the drum, this initial drive being preferably at an overspeed so as to 15 take up any accumulation of the slack resulting from the break of the web and the necessity of threading it on a new winding shaft.

The main object and feature of this invention is to so arrange the elements that the 20 accumulation of material on the winding shaft automatically decreases the speed of the driving means so that eventually the shaft will be driven at substantially the same surface speed as the drum with which it is 25 subsequently to engage.

In the accompanying drawings the invention is disclosed in a concrete and preferred form in which—

Fig. 1 is a side elevation of a winding machine, somewhat diagrammatically shown, embodying the invention; and

Fig. 2 is a view looking in the direction of arrow 2 of Fig. 1.

The winding means consist here of a drum 10 with which is preferably associated an abutment member that may take the form of a second drum 11, the two drums being spaced apart and rotatable in the same direction. Only drum 10 may be driven positively as by means of belt 12 but, if desired, both drums may be driven by a silent chain 13 or otherwise. The auxiliary winding means may take the form disclosed in the application referred to in which a pulley 14 engages with a complementary pulley on the winding shaft but, in the present instance, it is preferred to have a surface winding roll 14 extending the full length of the winding shaft; and this roll 14 may be driven in any suitable way as by means of belt 15 and suitable pulleys from shaft 16. A suitable support, here consisting of two arms 17 on shaft 18, is provided for the reception of winding shaft 19. Arms 17 have inclined open bearing sockets 20 for the reception of

blocks 21 carrying the winding shaft. The paper is fed between drum 10 and winding shaft 19 and wrapped around the latter. At this time, the winding shaft is not in contact with drum 10 because of the position of arms 17 against stop 24. Belt 15 is here shown as being associated with a suitable speed-change device and this may conveniently take the form of cone pulleys 100 and 101 together with a belt shifting member 102 of conventional construction. At the beginning of the winding operation, the surplus winding roll is driven at an overspeed; that is to say, faster than the web is supplied and faster than the surface speed of drum 10. In this way, any slack that may have accumulated during the change from one winding shaft to another will be taken up. It will be understood, however, that as the material accumulates on the winding shaft 19, it will eventually come into engagement with surface drum 10 and means are therefor provided for controlling the speed-change means by the accumulation of material on the winding shaft or by the movement of arm 17 or of some other member bearing a relation to the movement of said arm 17. In the present instance movement of belt-shifting member 102 is accomplished by means of a bell-crank 103, one arm of which engages belt-shifting member 102 and the other arm of which is engaged by a member 104 conveniently carried by one of the arms 17. It will be seen therefore that as the material accumulates on the winding shaft, arm 17 will swing around the pivot 18 and will thereby move member 104 in an upward direction; and member 104, being beneath the upper arm of bell-crank 103, will cause a tilting movement thereof

and then effect a sidewise movement of belt-shifting member 102 to move belt 15 on the cone pulleys and thereby gradually reduce the speed of surface-winding roll 14. During the subsequent operation of the machine, arms 17 are swung so as to bring winding shaft 19 into the valley between drums 10 and 11 and eventually, after sufficient material has been accumulated, the completed roll is removed from the machine by means described in the application referred to or in any other suitable manner.

I claim:

1. A winding machine including: a winding shaft, a surface winding drum to wind

material on the shaft, means for initially supporting said winding shaft out of contact with the drum, driving means, to rotate said shaft at an overspeed while out of contact with the drum to initiate the winding operation for engagement with the drum, including speed-change means actuated by the accumulation of material on the shaft to decrease the speed thereof.

10. 2. A winding machine including: a winding shaft, a surface winding drum to wind material on the shaft, a surface winding roll spaced from said drum to initiate the winding operation of the shaft, means for initially supporting said winding shaft between the drum and roll but out of contact with the drum and in contact with the roll, driving means, to initially rotate said roll at an overspeed, including a speed-change means actuated by the accumulation of material on the shaft to decrease the speed of said roll so that when the accumulated material rests on both the drum and the roll, said drum and roll will rotate at substantially the same surface speed.

3. A winding machine including: a surface winding drum, a winding shaft, means for supporting said winding shaft out of contact with the drum, driving means to rotate said shaft while out of contact with the drum at an overspeed to initiate the winding

operation before engagement with the drum, means for moving the winding shaft to bring the accumulated material thereon into engagement with the drum to thereby continue the winding operation, and a member following the movement of the shaft-supporting means to effect a decrease in the speed of the driving means as the winding shaft approaches the drum.

4. A winding machine including: a winding shaft, a surface winding drum to wind the material on the shaft, a surface winding roll in spaced relation to the drum to initiate the winding operation of the shaft, means for initially supporting said winding shaft between the drum and roll but out of contact with the drum and in contact with the roll, driving means to initially rotate said surface winding roll at an overspeed, means for moving the winding shaft to bring the accumulated material thereon into engagement with the drum to thereby continue the winding operation, and a member following the movement of the shaft-supporting means to effect a decrease in the speed of the driving means as the winding shaft approaches the drum.

Signed at New York, in the borough of Brooklyn, county of Kings, and State of New York, this 7 day of August, 1925.

JAMES A. CAMERON.
